UNITED STATES PATENT OFFICE.

JULES ERNEST LOUIS PUGET, OF PARIS, FRANCE, ASSIGNOR TO SOCIETE INDUSTRIELLE DES TELEPHONES (CONSTRUCTION ELECTRIQUE, CAOUTCHOUC, CABLES), OF PARIS, FRANCE.

RELAY FOR TELEPHONE CIRCUITS.

Application filed February 18, 1921. Serial No. 445,554.

To all whom it may concern:

Be it known that I, Jules Ernest Louis Puget, a citizen of the Republic of France, residing at Paris, France, have invented certain new and useful Improvements Relating to Relays for Telephone Circuits; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The invention relates to a reversible amplifier or reversible telephonic relay for telephone systems and consists in improvements by which efficient communication is maintained between two telephone lines of any characteristics.

The invention is based on the following simple consideration:

If v is the potential difference between the grid and the filament of a triode valve, v' the potential difference between the plate and the filament and i the current between the plate and the filament, these three quantities are connected by a linear relation:

$$(1) \quad i = av + bv'$$

If the external circuit of the plate-filament current has two paths in parallel (Fig. 1) traversed respectively by currents i' and i'' there exists between each of these currents v' and v'' and the differences of potential v and v linear relations of the form (1).

If s' and s'' are the impedances of each of these two paths:

$$(2) \quad i' = \frac{-v}{s'} \quad i'' = \frac{-v}{s''}$$

also:

$$(3) \quad i = i' + i''$$

The linear nature of the equations (1), (2) and (3) shows that the elimination of i' and i'' , for example, between the equation (1), the first of the equations (2) and the equation (3) gives a linear equation in v' , v and v .

It is easily seen that:

$$(4) \quad v' = av + \left(b + \frac{1}{s'} \right)v$$

Also:

$$(4') \quad v'' = av + \left(b + \frac{1}{s''} \right)v$$

These equations are also of the type (1). They have this peculiarity, that by modifying the impedance of one of the paths open to the plate filament current, the current circulating in the other path is modified, the law of variation being hyperbolic.

This considerably increases the range of regulation.

In the preceding expressions, as also in those set out later, the notations represent vectors in the usual manner.

No supposition has been made as regards the nature of the impedances s' and s'' ; they can be the resultant of any combination of resistances, self-inductances, capacities, even of negative resistances.

Figure 1 is a diagram illustrating the principles involved in the invention.

Fig. 2 is a diagram of a simple construction of telephone relay embodying the invention.

Fig. 3 is a diagram showing means to prevent reaction between two trunk lines.

In every system of a reversible amplifying relay interposed between two telephonic lines L_1 , L'_1 and L_2 , L'_2 , part or even the whole of the energy coming, for example, from the up line L_1 , L'_1 serves to excite the relay which then transmits over the line an increased quantity of energy. As the system is reversible it happens, if special precautions are not taken, that one part of this energy reacts to excite the relay, whence a sort of secondary amplification arises, and so on. According to the manner in which these superposed amplifications combine, the final result is either a super-excitation of the relay which starts to whistle, or an under-excitation and a diminution of the amplifying power of the relay.

According to the invention the reactions due to the secondary excitations are elimi-

nated by simple means. This is obtained by mounting on the line at a suitable point and under certain conditions a balancing arrangement consisting of a triode valve provided with means for modifying the characteristics of the valve.

Fig. 2 shows diagrammatically an arrangement according to the invention in which there is only one amplifying step. 10 In the diagram, L_1, L'_1 denote the two wires of the up circuit, line L_2, L'_2 , the two wires of the down circuit.

The wires L'_1, L'_2 are directly connected together at a point o from which also certain shunt circuits are taken; the other wires L_1, L_2 are connected by the secondary s_1 of a transformer T_1 , certain shunt circuits being connected to the terminals a and b of this secondary.

20 The system comprises essentially:

A triode valve A_1 , called the balancing valve, a triode valve A_2 , called the amplifying valve, a transformer T_1 for the valve A_1 , the transformer T_2 and a shunt R for the plate filament circuit of the balancing valve A_1 .

In the diagram a single plate battery B is shown in order to establish the potentials of the plates of the two valves, but two batteries for heating the filament, one for each of the valves A_1 and A_2 . This arrangement is immaterial as concerns the invention. A plate battery might be supplied for each of the two valves or a single heating battery for the two filaments. If the potentials of the plates P_1 and P_2 are determined by means of a single battery B it is necessary to insert self-inductances L_1, L'_1, L_2, L'_2 and capacities C_1 and C_2 in the usual manner, but this also is immaterial as regards the invention. b_1, b_2, r_1, r_2 denote respectively the heating batteries and the regulating resistances of the filaments of the valves A_1, A_2 .

45 The action of the arrangement is as follows:-

When a conversation is exchanged between the up line L_1 and L'_1 and the down line L_2, L'_2 , a difference of potential is set up between the point o of the conductor $L'_1, o L'_2$ and the point b of the conductor $L_1, a b L_2$. This difference of potential gives rise to a current which traverses the primary p_1 of the transformer T_1 , the circuit being formed, for example, over the shunt R connected at Q to the primary p_1 . The current in p_1 induces through the secondary s_1 of the transformer T_1 a difference of potential u_1 between the filament F_1 and the grid G_1 of the amplifying valve A_2 . The plate current which traverses the primary p_2 of the transformer T_2 reproduces and amplifies the exciting current which circulates in the primary p_1 . The transformer T_2 sets up, consequently, between the two points a and b

a telephonic electromotive force E depending on the initial exciting electromotive force E applied between the points o and b .

If the valves and the transformers T_1 and T_2 are suitably chosen amplification will 70 take place.

The secondary amplification can be avoided if the electromotive force E applied between a and b does not set up any current in the primary p_1 of the transformer T_1 . 75

Also, by virtue of the equations (4) and (4') the current i_1 in the primary p_1 depends on the potential v_1 between the plate and filament and the potential u_1 between the filament and grid of the valve A_1 , and 80 is given by the formula:

$$(5) \quad i_1 = a_1 u_1 + \left(b_1 + \frac{1}{R} \right) v_1$$

where R is the resistance of the shunt R ; 85 a_1 and b_1 being the constants of the valve A_1 , under the existing conditions.

Also, if we call z_1 and z_2 the respective inductances of the up and down lines, i_2 the current which circulates in the secondary of 90 the transformer T_2 , neglecting the grid current:

$$(6) \quad u_1 = z_1 i_2$$

(difference of potential between a and o) 95

$$v_1 = -z_2 (i_1 + i_2) - p_1 i_1$$

(difference of potential between b and o)

The elimination of u_1 and v_1 between equations (5) and (6) gives:

$$(7) \quad i_1 \left\{ 1 + \left(b_1 + \frac{1}{R} \right) (z_2 + p_1) \right\} = i_2 \left\{ a_1 z_1 - \left(b_1 + \frac{1}{R} \right) z_2 \right\}$$

Equation (7) shows that the relation

$$(8) \quad a_1 z_1 = \left(b_1 + \frac{1}{R} \right) z_2$$

determines the condition that the current i_1 shall be zero and consequently the elimination of the secondary amplifications. 110

It should be noticed that the first equation (6) only holds as regards the currents resulting from the first amplification, that is, 115 if the electromotive force is located between a and b , since the electromotive force initially produced by the microphone in the line circuit has not been taken into account. In considering the initial exciting currents 120 it is necessary to modify this equation in taking into account the electromotive forces at the end of the line.

The expression (8) can be written:

$$(9) \quad \frac{b_1 + \frac{1}{R}}{a_1} = \frac{z_1}{z_2}$$

The manipulation of the shunt R combined, if necessary, with the regulation of 130

the temperature of the filament of the valve A_1 will permit this condition (9) to be realized. If k_1 denotes the constant of amplification of the valve A_1 , the shunt being removed, the absolute value of the relation

$$\frac{b_1 + \frac{1}{R}}{a_1} \text{ can vary from } \frac{1}{k_1} \text{ to infinity.}$$

10 If the factor z_2 is greater than $k_1 \times z_1$, it will be sufficient to reverse the connections, thereby interchanging z_1 and z_2 in order to render the regulation possible.

15 The means for regulating the triode valve also permits of realizing a duplicate mounting which, as is known, consists in joining the two line trunks by a double bridge which only permits the transformation of energy in one direction for each of the 20 bridges; this system avoids the reactions of one line trunk on the other.

Fig. 3 shows circuit arrangements for this case.

25 In the diagram, z'_1 and z'_2 represent artificial lines satisfying the conditions

$$a_1 z_1 = \left(b_1 + \frac{1}{R_1} \right) z'_1$$

$$a_2 z_2 = \left(b_2 + \frac{1}{R_2} \right) z'_2$$

In particular, if $a_1 = b_1 + \frac{1}{R_1}$ and $a_2 = b_2 + \frac{1}{R_2}$,

35 it will be sufficient to take $z'_1 = z_1$ and $z'_2 = z_2$, but this is not necessary.

Under these conditions an electromotive force from the line L_1, L'_1 applied between a_1 and a_2 will give rise after amplification in A'_2 , to an electromotive force applied between the terminals a_2 and b_2 . Current will circulate in the line L_2, L'_2 in series with the impedance z'_2 , but the relay A'_2 will not act. The action will take place in an identically similar manner for a transmission from L_2, L'_2 to L_1, L'_1 .

It is understood that the arrangements described by way of example are not limited and that modifications can be made without departing from the characteristic features of the invention. In particular, the characteristics of the balancing valve instead of being controlled by the shunt could be controlled by any other means, for example by modifying the temperature of the valve or the voltage of the plate battery.

Having thus described the nature of the said invention and the best means I know of carrying the same into practical effect, 60 I claim:

1. An amplifying relay allowing communication in both directions between two line circuits of any characteristics and comprising in combination an amplifying triode valve and a balancing triode valve, each

valve containing a filament, a grid and a plate electrode, batteries for heating said filaments, a transformer comprising primary and secondary coils, the said primary coil being inserted in one line wire and the said 70 secondary between the grid and the filament of said amplifying valve and a second transformer comprising primary and secondary coils, the said last mentioned secondary coil forming a connection between the corresponding line wires of the two circuits, the last mentioned primary being inserted between the plate of the amplifying valve and the negative pole of the battery heating its filament. 80

2. An amplifying relay allowing communication in both directions between two line circuits of any characteristics and comprising in combination an amplifying triode valve and a balancing triode valve, each valve containing a filament, a grid and a plate electrode, batteries for heating said filaments, a transformer comprising primary and secondary coils, the said primary coil being inserted in one line wire and the said secondary 90 between the grid and the filament of said amplifying valve and a second transformer comprising primary and secondary coils, the said last mentioned secondary coil forming a connection between the two lines, the last 95 mentioned primary being inserted between the plate of the amplifying valve and the negative pole of the battery heating its filament, and means for altering the temperature of the filaments of said valves and 100 means for altering the voltage applied to the plate electrode of the balancing valve.

3. An amplifying relay allowing communication in both directions between two line circuits of any characteristics and comprising in combination an amplifying triode valve and a balancing triode valve, each valve containing a filament, a grid and a plate electrode, batteries for heating said filaments, a transformer comprising primary and secondary coils, an adjustable shunt connected between the plate of said balancing valve and the negative pole of the battery for heating the filament of said balancing valve, the grid of said balancing 110 valve being connected to one line of a circuit and the plate electrode of said balancing valve being connected through the primary coil of said first mentioned transformer to the corresponding line of the 120 other circuit.

4. An amplifying relay allowing communication in both directions between two line circuits of any characteristics and comprising in combination an amplifying triode 125 valve and a balancing triode valve, each valve containing a filament, a grid and a plate electrode, batteries for heating said filaments, a transformer comprising primary and secondary coils, one end of said pri- 130

- mary coil being connected to the common junction of the corresponding line wires of the two circuits and the other end of said primary being connected to the plate of said 5 balancing valve, the ends of said secondary coil being connected respectively to the negative pole of the battery for heating the filament of said amplifying valve and to the grid of said amplifying valve, a second 10 transformer comprising primary and secondary coils, the ends of said primary being connected, respectively, to the plate of said amplifying valve and to the negative pole of the filament of said amplifying valve, 15 and the ends of said secondary being connected, respectively, to line wires of one circuit and to the corresponding line wires of the other circuit.
5. An amplifying relay allowing communication in both directions between two line circuits of any characteristics and comprising in combination an amplifying triode valve and a balancing triode valve, each 20 valve containing a filament, a grid and a plate electrode, batteries for heating said filaments, a transformer comprising primary and secondary coils, one end of said primary coil being connected to the common junction of the corresponding lines of the two circuits 25 and the other end of said primary being connected to the plate of said balancing valve, the ends of said secondary coil being connected, respectively, to the negative pole of the battery for heating the filament of said 30 amplifying valve and to the grid of said amplifying valve, a second transformer comprising primary and secondary coils, the ends of said primary being connected, respectively, to the plate of said amplifying valve and to the negative pole of the filament of said amplifying valve and to the grid of said amplifying valve, a second 35 transformer comprising primary and secondary coils, the ends of said primary being connected, respectively, to the plate of said amplifying valve and to the negative pole of the filament of said amplifying valve and to the grid of said amplifying valve, a second transformer comprising primary and secondary coils, the ends of said primary being connected, respectively, to the plate of said amplifying valve and to the negative pole of the filament of said amplifying valve, the ends of said secondary being connected, respectively, to a line wire of one circuit and to the corresponding line of the other circuit, an adjustable 40 shunt being inserted between the negative pole of the battery heating the filament of the balancing valve and the plate of said balancing valve.
6. An amplifying relay allowing communication in both directions between two line circuits of any characteristics and comprising in combination an amplifying triode valve and a balancing triode valve, each 45 valve containing a filament, a grid and a plate electrode, batteries for heating said filaments, a transformer comprising primary and secondary coils, one end of said primary coil being connected to the common junction of the corresponding line wires of the two 50 circuits and the other end of said primary being connected to the plate of said balancing valve, the ends of said secondary coil being connected, respectively, to the negative pole of the battery for heating the filament of said amplifying valve and to the grid of said amplifying valve and to the negative pole of the filament of said amplifying valve and to the grid of said amplifying valve.
7. An amplifying relay allowing communication in both directions between two line circuits of any characteristics and comprising in combination an amplifying triode valve and a balancing triode valve, each 55 valve containing a filament, a grid and a plate electrode, batteries for heating said filaments, a transformer comprising primary and secondary coils, one end of said primary coil being connected to the common junction of the corresponding line wires of the two 60 circuits and the other end of said primary being connected to the plate of said balancing valve, the ends of said secondary coil being connected, respectively, to the negative pole of the battery for heating the filament of said amplifying valve and to the grid of said amplifying valve, a second transformer comprising primary and secondary coils, the ends of said primary being connected, respectively, to the plate of said amplifying valve and to the negative pole of the filament of said amplifying valve, the ends of said secondary being connected, respectively, to line wires of one circuit and to the corresponding line wires of the other circuit, two circuits comprising capacities and inductances, a battery energizing said two circuits in parallel, said circuits substantially balanced and connected at similar points thereof to the respective plate electrodes of said valves. 70
8. Amplifying relays allowing communication in both directions between two line circuits of any characteristics, and comprising in combination an amplifying triode valve and a balancing triode valve in each circuit, each valve containing a filament, a grid and a plate electrode, batteries for heating said filaments, transformers in each line circuit, primary and secondary coils in each transformer, an artificial line in each circuit, the ends of said primary coils being connected, respectively, to the plate electrodes of said balancing valves and to one end of said artificial lines and the ends of 75 80 85 90 95 100 105 110 115 120 125 130

5 said secondary coils being connected, respectively, to the negative ends of the batteries heating the filaments of said amplifying valves and to the grids of said amplifying 10 valves, a second transformer in each circuit, primary and secondary coils in each of last mentioned transformers, the ends of said primary coils being connected, respectively, to the negative poles of the batteries heating the filaments of said amplifying valves and to the grids of said amplifying valves, the said secondary coils being inserted, respectively, in each line circuit and means for altering the voltage applied to the 15 plate electrode of said valves and means for altering the temperature of said filaments.

9. Amplifying relays allowing communication in both directions between two line circuits of any characteristics, and comprising in combination an amplifying triode 20 valve and a balancing triode valve in each circuit, each valve containing a filament, a grid and a plate electrode, batteries for heating said filaments, transformers in each 25 line circuit, primary and secondary coils in each transformer, an artificial line in each line circuit, the ends of said primary coils being connected, respectively, to the plate electrodes of said balancing valves and to one end of said artificial lines and the ends 30 of said secondary coils being connected, respectively, to the negative ends of the batteries heating the filaments of said amplifying valves and to the grids of said amplifying valves, a second transformer in each 35 circuit, primary and secondary coils in each of last mentioned transformers, the ends of said primary coils being connected, respectively, to the negative poles of the batteries heating the filaments of said amplifying valves and to the grids of said amplifying valves, the said secondary coils being inserted, respectively, in each line circuit and adjustable shunts connected between the plates of said balancing valves 40 and the negative poles of the batteries for heating the filaments of said balancing valves, the grids of each of the balancing valves being connected to one line wire of a corresponding line circuit and the plate electrodes of said balancing valves being connected through the primary coils of said first mentioned transformers to the respective circuits.

In testimony that I claim the foregoing 55 as my invention, I have signed my name.

JULES ERNEST LOUIS PUGET.
